UNITED STATES PATENT OFFICE.

JAMES H. GRAY, OF NEW YORK, N. Y.

ELECTRIC FURNACE.

Application filed November 13, 1920. Serial No. 423,867.

To all whom it may concern:

Be it known that I, JAMES H. GRAY, a citizen of the United States, and resident of the city, county, and State of New York, 5 have invented certain new and useful Improvements in Electric Furnaces, of which the following is a specification.

My invention aims to provide certain improvements in electric furnaces and particularly in the means for holding and adjusting 10 the electrodes.

The accompanying drawings illustrate an embodiment of the invention.

Fig. 1 is a side elevation of a furnace 15 equipped with my improvement;

Fig. 2 is an enlarged view in longitudinal section of the electrode holding and adjusting means;

Figs. 3 and 4 are sections respectively on 20 lines 3—3 and 4—4 of Fig. 2;

Fig. 5 is a section on the line 5—5 of Fig. 2;

Fig. 6 is a cross-section of an alternative form of supporting arm.

25 Referring to the embodiment of the invention illustrated the furnace 1 has on its bottom a rocker 2 resting on a curved track 3, the furnace being tilted to the position shown in dotted lines by means of a link 4 extending to any suitable gearing. The furnace and tilting mechanism thereof constitute no part of this invention and may be of any usual or suitable design. The roof 5 of the furnace is pierced for the passage of 30 the electrodes 6 through the usual cooling rings 7. Each electrode has to be adjusted vertically and separately from the others and is equipped with the holder and adjusting means hereinafter described.

40 To permit the tilting of the furnace without moving the electrodes lengthwise, the supporting and adjusting mechanism is mounted on the furnace and tilted with it. Each electrode is mounted in a clamp 8 which is connected at its rear end to a horizontal arm or bus bar 9 which is connected by means of flexible cables 10 to the transformer or other source of supply, the cables being of a length sufficient to permit the tilting 45 of the furnace as shown. The center of rotation of the tilting furnace is at 11. The cables 10 extend upward from their connection to the bus bar, or supporting arm. As

the point of connection, therefore, swings upward as well as horizontally, during the 55 tilting of the furnace, the amount of take-up on the cables 10, or the amount of slack which has to be allowed in these cables, is comparatively little. A much shorter connection through such cables is established 60 than where their two ends are in horizontal alignment with each other or nearly so, as has been the usual practice heretofore.

For the heavy currents needed in electric arc furnaces, the reactance in the cables, 65 being proportional to their length, is very considerable. By this arrangement I have reduced such length and saved the loss of current by such reactance and also provided an arrangement by which a greater quantity of current can be put into the furnace.

I have also arranged the motors and mechanism for adjusting the electrodes entirely below the cables 10 so as to avoid loss of current which has occurred in previous installations by reason of the interference of the metal in the adjusting mechanism and supports surrounding or passing 75 between such cables.

For this purpose each of the arms 9 which 80 with the brackets 8 form the holders for the electrodes is mounted on a post 12 extending downward therefrom along the side of the furnace and this post is elevated and lowered by mechanism also mounted on the side of the furnace below the level of the 85 arms 9. On top of each post 12 is a cap 13 on which the arm is mounted with insulating material 14 interposed in the joint. On the lower end of the post is mounted a pulley 15. Brackets 17 in the form of channels are mounted on the furnace and carry 90 guide channels 18 between which are guided sleeves 19 and 20 (Figs. 3 and 5) fastened on the upper and lower ends of the post 12, the sleeves 19 and 20 being formed with 95 flanges 21 which fit into the corners of the rectangular guideway formed by the channels 18. Fastened on the outside of the channels 18, are reinforcing channels 22.

On the inner edges of the guideway near 100 the top are mounted bearing blocks 23 carrying a guide roller 24 against which bears the inner face of the guide block 19. On the lower end of the guideway on its outer side is mounted a similar guide roller 25 105

against which bears the outer face of the lower guide block 20. These guide rollers 24 and 25 are arranged to take the lateral bearing of the post due to the weight of the 5 overhanging arm and electrode.

At the upper end of the guideway, on the outer side, are mounted brackets 26 carrying fixed guide pulleys 27. Cables 28 are attached at their inner ends to the brackets 17, 10 passed downward over the pulleys 15 and up over the fixed pulleys 27 and thence to a winding drum 28 driven from a motor 29 which is mounted on a bracket 30 on the outer face of the guideway. When the cable 15 is taken up on the drum it lifts the truck or post 12 and with it the arm 9 and electrode 6. When the furnace is tilted all the parts described move together, retaining their relative 20 positions and preventing longitudinal movement of the electrodes.

Each arm 9 is formed at its rear end with a hollow bracket 31 and the cables 10 are fastened around the outside thereof, as shown in Fig. 4. A cooling system is provided for each supporting arm and clamp. The arm is preferably made in the form of an I-beam (Fig. 4) with passages 32 running longitudinally through it and leading out near the rear end of the arm to the 30 usual or any suitable water connections for supply and discharge, as indicated, for example, at 32^a and 32^b, Fig. 2. One of the passages 32 is connected near the forward end of the arm through pipes 33 to the inlet 35 end of a water passage in the clamping arm 8, and the discharge end of the same passage is connected through a pipe 34 to the opposite passage 32 of the arm.

In Fig. 6, there is shown an alternative 40 form of supporting arm 9^a which is box shaped with a diaphragm 35 which divides the space within the arm into two passages 36 for the circulating of cooling water.

The arms 9, or 9^a, which serve both to 45 support the electrodes and to convey current thereto may be made in various forms, integral or built up. They may be made of copper for greater conductivity. Or they may be made of steel with copper bars extending along the top of them; the latter construction being useful particularly where the required current is so low as not to involve serious losses through reactance.

Though I have described with great particularity in detail a certain embodiment of 55 my invention, yet it is not to be understood therefrom that the invention is restricted to the embodiment disclosed. Various modifications thereof may be made by those skilled

in the art without departure from the invention as defined in the following claims.

What I claim is:

1. An electric furnace having electrode holders comprising arms extending across the top of the furnace and carrying the weight 65 of said electrodes and also serving as conductors to convey current to said electrodes, said arms having passages formed therein to permit the circulation of a cooling medium in intimate contact therewith. 70

2. An electric furnace having electrode holders comprising a clamp and a supporting arm therefor, said arm having passages formed therein to permit the circulation of a cooling fluid in intimate contact therewith. 75

3. An electric furnace having electrode holders comprising arms carrying the weight 80 of the electrodes and serving as conductors to convey current to said electrodes and having connected to the rear ends thereof flexible cables extending to a fixed point above said holders so that cables of minimum length can be used thereby cutting down the reactance and attendant current losses.

4. An electric furnace having electrode 85 holders comprising arms extending across the top of the furnace, posts extending down from said arms along the side of the furnace guides on the furnace for said posts located below the roof of the furnace, motors 90 mounted on the furnace and cables operatively connected with said motors and said posts whereby the electrodes are raised and lowered.

5. An electric furnace having electrode 95 holders comprising arms extending across the top of the furnace, posts secured below said arms, guiding means for said posts located wholly below said arms and motors mounted on the furnace operatively connected with cables engaging the lower ends 100 of said posts and arranged to lift and lower said arms, said guiding means being so arranged that said arms never project therebetween.

6. An electric furnace having electrode 105 holders comprising arms extending across the top of the furnace, posts extending down from said arms along the side of the furnace, guides on the furnace for said posts and motors mounted on said furnace and cables connected to said furnace and to said motors and engaging in their bights the said posts so as to lift and lower the same as the 110 motors are operated.

In witness whereof, I have hereunto signed my name.

JAMES H. GRAY
